UNITED STATES PATENT OFFICE.

WALTER CHARLES MAGEE, OF NEW YORK, N. Y., ASSIGNOR TO STEPHEN SANFORD & SONS, OF AMSTERDAM, NEW YORK.

DESIGN FOR CARPETING.

SPECIFICATION forming part of Design No. 31,166, dated July 4, 1899.

Application filed February 17, 1899. Serial No. 705,900. Term of patent 3½ years.

To all whom it may concern:

Be it known that I, WALTER CHARLES MAGEE, a citizen of the United States, residing at New York, in the county of New York and State of New York, have invented and produced a new and original Design to be Worked into or upon Carpeting or Similar Fabrics; and I do hereby declare that the drawing accompanying this specification gives and conveys to any one skilled in the art of carpet-weaving a clear understanding of the same that is sufficient to enable such person to use my invention.

The said drawing is a face view of the carpet embodying my design, which is in its rel-

ative aspect of ornamentation in Japanese style, consisting of scrolls covering the ground and small diamond-shaped set figures on top. Ornamentation in center of small set figures is in Japanese style, all arranged and treated as shown in the said drawing.

What I claim, and desire to secure by Letters Patent, is—

The design for carpeting substantially as shown and described.

WALTER CHARLES MAGEE. [U. S.]
